UNITED STATES PATENT OFFICE.

LOUIS BOYD, OF CONNELLSVILLE, PENNSYLVANIA.

LEAF TURNER.

Application filed November 1, 1926. Serial No. 145,532.

This invention aims to provide a novel means for turning over the leaves of a book, in order to display wall paper or other commodities, the machine being motor-actuated, and requiring no continued attention on the part of an operator.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Figure 1 shows in elevation, a device constructed in accordance with the invention;

Figure 2 is an elevation wherein the machine is viewed at right angles to the showing of Figure 1;

Figure 3 is an enlarged vertical sectional view, parts being broken away;

Figure 4 is a fragmental horizontal section showing one of the springs which engages the book.

In carrying out the invention, there is provided a frame, which may be variously constructed, without jeopardizing the utility of the device hereinafter described. The drawings show a frame 1, embodying a base 2 and vertical parallel posts 3 secured thereto, the posts being connected at points adjacent to their upper ends, by a top bar 4. A horizontal shaft 5 is journaled in the posts 3 near to the lower ends thereof, and any suitable means may be supplied for rotating the shaft.

A satisfactory means for rotating the shaft 5 embodies a worm wheel 6, secured to one end of the shaft, the worm wheel being in mesh with a worm 7 which, as Figure 2 shows, is secured to a shaft 8 forming part of a motor 9, the shaft being journaled in a bearing 10 on the base 2. The motor 9 may be an electric motor.

A standard 11 is mounted on the base 1 at a point about midway between the posts 3. The standard 11 has horizontally spaced arms 12, one of which terminates in a horizontal support 14 which overhangs the other

arm. The support 14 is so called because it holds in an approximately vertical position, a guard which includes a frame 15 and a foraminous body 16 (preferably wire netting) carried by the frame. A horizontal shaft 17 is journaled in the arms 12 of the standard 11, and to the shaft, a suction fan 18 is secured, the shaft being driven by a belt 20 engaged about a pulley 21 on the shaft 17, and about a pulley 19 on the shaft 17. The suction fan 18 is located outwardly of the guard 16-17 but is placed close enough to the guard so as to create, through the foraminous body 16 of the guard, a suction which is strong enough to carry out an operation which will be described hereinafter.

Sprocket wheels 22 are secured to the shaft 5, and idle sprocket wheels 24 are journaled on the posts 3 near to the upper end thereof. About the sprocket wheels 22 and 24 are engaged sprocket chains 23. The ends of a rod 25 are connected to the chains 23, the rod acting as a turner for operating the leaves 26 of a book, the leaves being held together by a rigid binding 27, hangers 28 being mounted on the binding, and forming part thereof, the top bar 4 extending through the hangers, and the construction being such that, upon occasion, the binding 27 of the book can be swung entirely around the top bar 4. There is an abutment, such as a cotter pin 29, in the bar 4, near to one end thereof. One of the hangers 28 is held frictionally against the abutment 29 by means of a compression spring coiled around the top bar 4 and engaging the other hanger 28, and a coupling 31 which is interposed in one of the posts 3. To the other post 3, a spring tongue 32 is secured at one end, as shown at 33, the tongue overlapping and engaging the binding 27 of the book, and, more specifically, engaging the end of one of the hangers 28, as Figures 1 and 4 will show. Projections 34, in the form of rigid arms, are secured at their upper ends to the binding 27 of the book, the lower ends of the arms slanting away from the leaves 26 of the book, as shown in Figure 3.

Through the instrumentality of the hangers 28 and the top bar 4, the book, including the leaves 26 and the binding 27, is mounted for rotation about a horizontal axis. The sprocket chains 23 constitute a means for mounting the leaf turner 25 for movement in an orbit about the book. The fan 18 creates a suction and draws the free

ends of the leaves 26, one at a time, against the foraminous body 16 of the guard, and into the path of the turner 25, whereby, when the turner moves upwardly, as shown in Figure 2, the turner will move the leaves 27 backwardly and downwardly with respect to the axis represented by the rod 4, to form, as leaf after leaf is turned over, a pendant mass of leaves, which is marked 5 by the numeral 35 in Figure 3. This pendant portion of the book, shown at 35, engages with the backwardly and outwardly extended lower ends of the projections 34 on the binding of the book: and due to 10 this circumstance, as well as to the fact that the weight of the part 35 tends to cause the binding 27 of the book to make a partial rotation with respect to the rod 34, the projections 34 swing forwardly, that 15 is, to the right in Figure 3, and rest at their lower ends against the rearmost leaf of the book. Ultimately, the fan 18 draws the rearmost leaf against the foraminous body 16 of the guard. Then the leaf turner 25 20 moves up behind the rearmost leaf and engages directly with the projections 34 which, then, are in the position shown in dash line at 36 in Figure 3. The upwardly and rearwardly moving turner 25, cooperating with 25 the projections 34, completes the rotation of the binding 27 of the book upon the rod 4, and the book thereupon is restored to its original position, that is, to the vertically hanging position shown in solid lines in 30 Figure 3. The cycle above described will be repeated so long as the operator permits the motor 9 to drive the shaft 8.

The motor 9, the shaft 8, the worm 7, the worm wheel 6, the shaft 5, and the sprocket 35 wheels 22, together with the sprocket chains 23, constitute mechanism for operating the leaf turner 25. The fan 18, which constitutes means for moving the free ends of the leaves, is also driven from the motor 9, by way of the shaft 8, the pulley 21, the belt 20, the pulley 19, and the shaft 17.

It has been pointed out hereinbefore that the turner 25 engages the arms or projections 34 to complete the rotation of the binding 27 about the rod 4, and the aforesaid rotation is yieldably resisted by a brake mechanism including the spring tongue 32, and the spring 30 which holds one of the hangers 28 in engagement frictionally with the abutment 29. 55

What is claimed is:—

1. In a device of the class described, a book including a binding and leaves, means for mounting the binding for rotation about an axis, a leaf turner, means for mounting 60 the turner for movement in an orbit about the book, means for moving the free ends of the leaves, one at a time, into the path of the turner, whereby the turner will turn the leaves backwardly and downwardly 65 with respect to said axis, to form a pendant portion, and a projection on the book and movable against the last leaf of the book when the binding makes a partial rotation with respect to said axis, due to the weight 70 of said pendant portion, whereby the turner will engage directly with the projection after the last leaf has been turned, and complete the rotation of the binding on said axis, thereby to restore the book to its 75 original position.

2. A device of the class described, constructed as set forth in claim 1, and further characterized by the provision of brake mechanism yieldably resisting the rotation 80 of the binding with respect to said axis.

3. A device of the class described, constructed as set forth in claim 1, and further characterized by the provision of mechanism for operating the leaf turner, and the 85 means for moving the free ends of the leaves, from a single source of power.

In testimony that I claim the foregoing as my own, I have hereto affixed my signature.

LOUIS BOYD.
